Primary Examiner — Catherine S Posthauer*Assistant Examiner* — Joan E. Diehl(74) *Attorney, Agent, or Firm* — Dickinson Wright PLLC(57) **CLAIM**

We claim the ornamental design for a foam packaging element, as shown and described.

DESCRIPTION

FIG. 1 is a top-front perspective view of a foam packaging element;

FIG. 2 is a front view of the foam packaging element of FIG. 1;

FIG. 3 is a rear view of the foam packaging element of FIG. 1;

FIG. 4 is a left side view of the foam packaging element of FIG. 1;

FIG. 5 is a right side view of the foam packaging element of FIG. 1;

FIG. 6 is a top view of the foam packaging element of FIG. 1; and,

FIG. 7 is a bottom view of the foam packaging element of FIG. 1.

The broken lines in the drawings illustrate portions of the foam packaging element that form no part of the claimed design.

1 Claim, 4 Drawing Sheets(56)
